UNITED STATES PATENT OFFICE

FREDERICK O. GRAY, OF DAYTON, OHIO, ASSIGNOR TO OHMER FARE REGISTER COMPANY, OF DAYTON, OHIO, A CORPORATION OF NEW YORK.

TAXIMETER FARE-COUNTER CONTROL.

Application filed May 12, 1923. Serial No. 638,455.

To all whom it may concern:

Be it known that I, FREDERICK O. GRAY, a citizen of the United States, residing in the city of Dayton, county of Montgomery, 5 and State of Ohio, have invented certain new and useful Improvements in Taximeter Fare-Counter Controls, of which I declare the following to be a full, clear, and exact description.

10 This invention relates to a fare counter actuating device especially adapted for use in a taximeter. More specifically, the invention is an improvement on the fare counter actuator controlling devices described in my co-pending application Serial 15 No. 638,454, filed May 12, 1923. In said application a cam is provided which is adapted to be driven either from the ground wheel 20 of a vehicle or from a clock. This cam has a plurality of lobes or active surfaces which are engaged by a follower arm which acts to intermittently actuate a fare counter. It is customary in a taxicab business to make a minimum charge for hiring a vehicle, for 25 this minimum charge to render a certain number of units of service, and when the minimum charge has been consumed, to actuate the fare counter at the beginning of subsequent units of service. In my co-pending 30 application above referred to, the cam follower, which is in the form of an arm adapted to rock the shaft on which it is mounted, is, during the period of service corresponding to the initial charge, retained 35 out of operative relation with the cam which actuates it by means of a latch which is spring pressed toward effective position. This latch is rendered ineffective when the service rendered has consumed the initial 40 charge by means of a pin suitably mounted on the actuating cam. It will be seen that the use of the device thus described is limited by the condition that the service to be rendered for the initial fare shall not exceed 45 the service represented by one complete rotation of the actuating cam. Suppose for example, that the actuating cam comprises four lobes and that it is desired to actuate the fare counter every quarter mile of distance traveled after the initial charge has 50 been consumed. The shaft which carries the actuating cam will be geared to the shaft operated by the ground wheel in such a way that the cam shaft will turn one full revolution while the vehicle travels one mile, dur-

ing which each of the four active surfaces of the cam will have actuated the fare counter once. With this arrangement the distance to be traveled before the fare counter becomes operative cannot exceed one mile by reason of the fact that the actuating cam makes one complete rotation per mile of travel, and the pin mounted on this cam must inevitably release the operating arm latch on the first rotation of the cam. 60

The object of the present invention is to provide a latch device which is not subject to the limitation above discussed, that is, a device which permits of more than one complete rotation of the actuating cam shaft 70 before the fare counter operating arm is released and becomes effective.

A further object of the invention is to provide a latch device which shall have two effective positions, and means associated 75 with the cam effective on the first rotation thereof to move the latch from its first effective position to its intermediate position.

A further object of the invention is to provide a latch and control devices for the 80 same, associated with the cam, which shall permit of more than one revolution of the cam before the latch is released.

My invention is herein described as applied 85 to a taximeter of the type disclosed in the Patent 1,136,164 of April 20, 1915, to Ohmer and Bridenbaugh.

In the drawings:

Fig. 1 is a front elevation of the parts constituting my invention together with such 90 elements of the Ohmer taximeter as are necessary to show its application thereto. Fig. 2 is a side elevation of the parts shown in Fig. 1. Fig. 3 is a view similar to Fig. 2 but showing the latching device in the intermediate position which it occupies after having been affected by the first of two operating studs carried by the cam. 95

The actuating shaft 10 is adapted to be 100 rotated at a rate proportional either to the distance traveled or to the time consumed in waiting by mechanism fully described in the patent to Ohmer et al. above referred to or in my co-pending application. Said shaft 10 carries the four lobed actuating cam 11, the surface of which is followed by the operating arm 12 rigidly attached to shaft 13. The shaft 13 actuates the fare counter in the manner described in the patent above referred to. 110

The flag or control shaft 14 carries a cam 15 which by its engagement with a stud 16 on the operating arm 12, holds the operating arm out of contact with the actuating cam until the flag shaft 14 is moved to the position it occupies when the vehicle is in hire. Loosely mounted on the shaft 14 is a latch 17 which engages a lug 18 mounted in the operating arm 12 when the operating arm is released from the cam 15 by the rotation of the flag shaft. The operating arm 12 is pressed toward the actuating cam 11 by spring 19. The latch 17 is formed at its upper end with two shoulders, either of which may engage the lug 18 and hold the operating arm 12 ineffective. When the operating arm is raised to ineffective position by the return of the flag shaft 14 to "For hire" position, the latch 17 assumes the position shown in Fig. 2. The latch is provided at its lower end with a horizontally extending portion 20, and the actuating cam 11 carries two studs 21 and 22, the stud 21 being located nearer the center of the cam than stud 22, as clearly illustrated in Fig. 2. Stud 22 is short and when the latch 17 occupies the position shown in Fig. 2, this stud will pass by the latch idly. The stud 21, however, is of such a length as to engage the side of the upwardly extending portion of the latch and to move the latch from the Fig. 2 position to the Fig. 3 position. This movement does not render the latch ineffective on the operating arm 12 as Fig. 3 clearly shows, but in this position the horizontally extending portion 20 of the latch is in the path of the stud 22; accordingly when in the rotation of the cam 11 the stud 22 again comes to a position adjacent the latch, the horizontal portion 20 will be engaged by the stud 22 and the latch will be swung to an extent sufficient to release the operating arm 12. With this arrangement it is possible for the actuating cam 11 to make $1\frac{3}{4}$ revolutions before the operating arm is placed in effective relation thereto; thus the number of units of service which can be rendered for an initial fare is greatly increased.

Variations in the structure herein specifically described and illustrated in the drawings will be resorted to within the scope of the appended claims.

55 I claim:

1. In a taximeter, a register operating arm, a device adapted to actuate said arm, a latch retaining said arm inoperative, means for setting said latch in a secondary latching position, and devices for moving said latch from said secondary position to ineffective position.

2. In a taximeter a register operating arm, a cam adapted to actuate said arm, a latch for retaining said arm out of opera-

tive relation with said cam, and means associated with said cam for rendering said latch ineffective, said means comprising two lugs engaging said latch in sequence.

3. In a taximeter, in combination, a fare counter operating arm, a cam adapted to actuate said arm, means retaining said arm out of operative relation with said cam, means mounted on said cam for positioning said retaining means during the first rotation of said cam, and other means mounted on said cam for disabling said retaining means on the second rotation of said cam.

4. In a taximeter, in combination, a fare counter operating arm, a cam adapted to actuate said arm, means retaining said arm out of operative relation with said cam, normally ineffective disabling devices for said retaining means, and means mounted on said cam for rendering said disabling devices effective.

5. In a taximeter, in combination, a fare counter operating arm, a cam adapted to actuate said arm, means retaining said arm out of operative relation with said cam, said means having a first effective position, an intermediate effective position, and an ineffective position, a device associated with said cam for moving said retaining means from its first effective position to its intermediate position, and a second device associated with said cam for moving said retaining device to ineffective position.

6. In a taximeter, in combination, a fare counter operating arm, a cam adapted to actuate said arm, a pivoted latch adapted to engage and retain said arm out of engagement with said cam, said latch having two effective positions, means for moving said latch from its first effective position to its second effective position, and a latch releasing stud on said cam effective only when said latch is in said second effective position.

7. In a taximeter, in combination, a fare counter operating arm, a cam adapted to actuate said arm, a pivoted latch adapted to engage and retain said arm out of engagement with said cam, said latch having a first effective position and an intermediate effective position, disabling means for said latch associated with said cam and effective only when said latch is in intermediate position, and other means associated with said cam for moving said latch from its first to its intermediate position.

8. In a taximeter, in combination, a fare counter operating arm, an actuating cam comprising a plurality of arm engaging surfaces, a pivoted latch adapted to engage and retain said arm out of engagement with said cam, said latch having a first effective position and an intermediate effec-

tive position, a latch engaging stud on said cam adapted to pass said latch idly when the latch is in its first effective position, and a second stud on said cam adapted to move said latch from its first effective position to its intermediate position.

9. In a taximeter, a fare counter operating arm, a rotating cam adapted to actuate said arm, means for retaining said arm in inoperative position, and means associated with said cam for disabling said retaining means, said disabling means comprising a releasing device which is ineffective on the first full rotation of said cam, but effective during its second rotation.

10. In a taximeter, in combination, a fare counter operating arm, a rotating cam adapted to actuate said arm, a lug on said arm, a pivoted latch comprising two shoulders at its upper end, either of which is adapted to engage said lug, a laterally extending flange at the lower end of said latch adjacent said cam, a stud on said cam adapted to engage said flange when one shoulder of said latch is engaged by said lug and to pass said flange when the second shoulder is engaged by said lug, a second stud on said cam adapted to engage a part of said latch adjacent said flange and move said latch from a position in which the second shoulder engages the lug to a position in which the first shoulder engages the lug, and a spring tending to draw said latch toward said lug.

11. In a taximeter a fare counter operating device, an actuator having an initial position and adapted to be driven at a rate proportional to either time consumed or distance traversed and to actuate said operating device, a retaining device having two

effective positions for retaining said operating device out of effective relation with said actuator, means associated with said actuator for moving said retaining device from its first effective position to its second effective position, and later from its second effective position to ineffective position, and a setting device for restoring said operating device to inoperative position and said latch to its first effective position.

12. In a taximeter, in combination, a fare counter operating device, an actuator, a first stud associated with said actuator, a second stud associated with said actuator, a retaining device for said operating device initially retaining the same inoperative and adapted to be moved to release the same by the successive action of said first and second studs, and a setting device adapted to restore said operating device, and said retaining device to initial position.

13. In a taximeter, in combination, an actuator, a fare counter operating device, a setting device, a cam associated with said setting device adapted in one position of such device to retain said operating device ineffective, a spring pressed retaining device adapted to retain said operating device ineffective when it is released by movement of said setting device, a plurality of devices associated with said actuator adapted by their successive action on said retaining device to release said operating means for co-operation with said actuator, said setting device being adapted on return thereof to initial position to restore said operating device to position to be engaged by said retaining device.

In testimony whereof I affix my signature.
FREDERICK O. GRAY.
